[57] CLAIM

The ornamental design for a hair spray shield for attachment to spray cans, as shown and described.

DESCRIPTION

FIG. 1 is a perspective view of a hair spray shield for attachment to spray cans showing my new design;
FIG. 2 is a side-elevational view;
FIG. 3 is a front-elevational view; and
FIG. 4 is a bottom plan view thereof.

The broken line showing a portion of a spray can in FIG. 2 is for illustrative purposes only.

FIG. 1

FIG. 2

FIG. 3

FIG. 4
